LINT COLLECTOR

Philip F. Maguire, Jr., Providence, R.I., assignor to Grinnell Corporation, Providence, R.I., a corporation of Delaware

Filed Apr. 19, 1961, Ser. No. 104,046

3 Claims. (Cl. 139—122)

This invention relates to shuttleless looms and more particularly to apparatus for collecting and removing lint and fly given off from certain areas of the loom during the weaving operations, this apparatus being fastened to and part of the loom.

Yarn which is used in weaving cotton or woolen cloth is formed from substantially parallel oriented fibers which are twisted together. These fibers occasionally have one end free of the yarn susceptible to being loosened or broken off. In the course of the weaving operation, for various reasons, these ends are often freed and together with loosened sizing matter form the lint and fly. The accumulation of this lint and fly on a loom which is processing cloth can, if permitted to go unchecked, become a very serious problem because of possible interference with the loom operation or if permitted to drop on the yarn or cloth may result in defects in the cloth.

The shuttleless loom by its name implies the absence of a shuttle to carry bobbins, wound with the filling yarn, across the warp threads on a loom. Instead, the filling is provided by flexible metal bands carrying the filling from yarn supply reels located at one end of the loom. These reels, until now have been located in a pie-shaped segment composed of two plates joined at an acute angle to each other and having a small opening in the apex of the angle through which the filling yarn was passed. As a result of this arrangement much lint and fly has been generated at the opening in the apex, since any upstanding ends in the yarn would rub at the opening and tend to break off. Further, the speedy unwinding of the yarn from the reels has been another factor in generating this unwanted matter because of the whipping about of the yarn as it comes off the reel. Until now the only feasible way of cleaning this area and preventing lint collection was by a hand operation.

My invention now continuously and automatically prevents unwanted lint and fly from accumulating. This is accomplished by my unique apparatus which, in a preferred form, totally encloses the supply reels and by judicious arrangement of blowing and sucking apparatus and filters, collects the lint and fly and prevents its dispersal to areas where it might interfere with the machinery or with the quality of the woven cloth.

The objects of my invention are that each shuttleless loom have its own collection system; that this system be located on the loom at a place where a large portion of the lint and fly is formed; and that the system operate continuously to collect said lint and fly before it has an opportunity to come to rest on the machinery surfaces or the woven cloth.

Consideration of the following specification and the drawing attached thereto will provide a better understanding of my invention.

In the drawing:

FIGURE 1 is perspective view of the preferred embodiment of my invention, mounted on a shuttleless loom.

FIGURE 2 is a side elevational view of my novel device.

FIGURE 3 is a plan section view taken along line 3—3 of FIGURE 2.

FIGURE 4 is a plan section view taken along line 4—4 of FIGURE 2.

FIGURE 5 is an enlarged perspective detail of one of the intake nozzles shown in FIGURE 4.

Viewing the drawings with greater particularity it is seen that 10 designates a shuttleless loom generally. Fastened to one end of said loom is my novel cleaning apparatus generally designated as 20.

5 The apparatus is fastened to the loom by a cast bracket, a showing of which has been omitted to more clearly present the novel components of my structure. Fastened to the unseen joining bracket are two support brackets, one of which is shown at 22. These brackets adjustably support bracket extensions 26 and 28 which in turn support 10 yarn supply reels 30 and 32. These reels are hingedly supported on pins 34 and 36.

The reels are contained within an enclosure formed by sidewalls 38 and 40 joined together at an acute angle to 15 form an apex 42. Above these walls is a top plate 46, and beneath the walls, a bottom plate 48. In the preferred embodiment of my apparatus this bottom plate slopes downwardly toward the front portion. As shown in the drawing, the segment thus formed is essentially pie-shaped, containing a rounded front portion 50. Extending across and partially up the front is a sheet metal apron 52. This apron leans outwardly at its top edge 53. Above the apron and covering the remainder of the front portion is a clear polyvinyl plastic curtain 54 suspended from a curtain rod 56 by standard molded nylon sliders 58. This curtain contains two side metal rods supports 60 and 62 which each contain a hole therethrough to receive a guide pin 64 and 66. Because of the outwardly extending edge 53 a more positive sealing engagement is provided between the curtain and the apron during operation of the apparatus.

Within the enclosure is a conduit, preferably a flexible suction hose 68 which extends from the top to almost the bottom of the front of the reel enclosure. This hose enters a lint collection chamber 70 above the reel enclosure. 35 At the lower portion of each of the sidewalls 38 and 40 is a rotatable nozzle. These are indicated by numerals 72 and 74. At the front end of the nozzles are protecting strips 76 and 78 joined to the bottom and sides of the 40 container, which prevent the unwinding yarn from tangling on the nozzles. This arrangement is clearly shown in FIGURE 5 of the drawing.

Above the reel enclosure is the lint collection chamber 70. This chamber is composed of sidewalls 90 and 92. Extending through sidewall 92 is a self contained suction 45 fan 94 which causes air to flow from the reel enclosure through the flexible hose 68 and into the chamber 70.

Contained within the chamber are filter screens 80, 82, 50 84 and 86 of a foraminous material, preferably woven metal mesh. These screens are insertable from the front of the chamber in guides which retain screens 80 and 82 in spaced parallel relation to each other and wall 90 and also 84 and 86 in spaced parallel relation to each other and wall 92. Screens 82 and 84, likewise screens 55 80 and 86 abut each other in sealing engagement at an acute angle substantially equal to the angle formed by walls 90 and 92. As a result of this relationship a small suction plenum chamber is formed between screen 80 and wall 90 and between screen 86 and wall 92. Thus, all the air being sucked into fan 94 must first pass through screens 80, 82, 84 and 86. The filter screens 80 and 86 are of a finer mesh than the filter screens 82 and 84. Therefore, when lint laden air passes through all the screens, filtration occurs on the surfaces of all the screens. 60 Any lint passing through filters 82 and 84 will be trapped by filters 80 and 86. Eventually a lint blanket will build up on these last two screens and increase the filtering efficiency since the blanket will also act as a filter.

The operation of my device is as follows:

As the suction fan 94 operates this causes a lowered pressure in chamber 70 which in turn instigates an air flow through the hose 68. This in turn lowers the pres-

sure in the container 20 and causes air to enter through the nozzles 72 and 74. These nozzles are rotatably adjustable so that they may be properly directed to cause an optimum air flow toward hose 68. Due to the fact that so many different types of cloth from different types of yarn may be woven on any single loom, a different setting of nozzles 72 and 74 may be required for each type of yarn to drive the maximum amount of lint toward hose 68. The presence of the sloping bottom of the container also aids in moving the maximum amount of lint toward hose 68. The hose has fastened at its bottom end a spring loaded disk clip 67 through which the connecting strand 69 is threaded. The strand 69 is the means by which the beginning of reel 32 is fastened to the end of reel 30 and thereby removes the requirement of doffing an empty reel as soon as all the yarn is expended. Normally the strand 69 would whip about due to the air movement, and as a result possibly break. The clip 67 retains the strand in a restrained but movable position and thus overcomes the whipping difficulty. Naturally, other suitable means for restraining strand 69 may be used in lieu of clip 67.

Air flowing toward and then up tube 68 carries with it any lint given off by the movement of the yarn 31 as it whips about while being withdrawn from reel 30 at a high speed and passes through the eye 42'. The lint is carried into chamber 70 and toward suction fan 94. Because of the restriction to flow area caused by the filter screens 84 and 86, part of the air carrying the lint will not flow directly through these screens to fan 94 but will have a portion that is required to be passed, as well, through filter screens 80 and 82. As a result lint will be deposited on all four filter screens 80, 82, 84 and 86, the larger particles on coarser screens 82 and 84 and the finer particles on screens 80 and 86. As the finer particles accumulate on screens 80 and 86 they will build up a felt layer between these screens and 82 and 84, which act to increase the efficiency of the filtration action. The air which is carrying this lint, once divested thereof, will pass into the plenum chamber formed by screens 80 and 86 and side walls 90 and 92 and then into the fan 94.

Periodically this chamber 70 and the filters may be inspected and cleaned through the doors 95 and 97, which are hinged to the outer casing.

The interior of container 20 may be periodically inspected by looking through the transparent curtain 54. Should something within the container require attention, either rod support 60 or 62 may be disengaged from guide pin 64 or 66 and the curtain slid to one side or the other on the rod 56. The most frequent operation which may occur in the container is that of replacing an empty reel. It is obvious that my unique apparatus will not present any noteworthy interference with such an operation since easy access is available to the reel supports which may be pivoted into position for easy loading and unloading.

It is, of course, to be understood that the details of my invention, described and illustrated, are merely illustrative and not limiting, as changes in details may be made by those skilled in the art without departing from the spirit and scope of the invention as claimed in the appended claims.

I claim:

1. In combination with a loom having a plurality of supply reels providing filling yarn to be woven:

(A) a container enclosing said reels,

(1) said container having a substantially flat bottom sloping downwardly towards one side of said container,

(B) a lint collection chamber joined to said container,

(C) a suction device connected to said chamber,

(D) a conduit having one end with access to the interior of said chamber and extending into said container with the other end adjacent the lowest portion of said bottom of said container,

(E) slidably removable filter means in said chamber

65

sealingly interposed between said one end of said conduit and said suction device,

(F) at least one elbow-shaped rotatable nozzle in a side wall of said container directed into said container toward the lowest portion of said bottom of said container and said conduit,

(1) said nozzle providing free passage of air from the exterior of said container to the interior in the form of a directable stream in accordance with the demand requirements of said suction device; whereby said stream may be directed along the bottom of said container toward said conduit to give optimum cleaning in accordance with the type of yarn on said supply reels.

2. In combination with a loom having a plurality of supply reels providing filling yarn to be woven:

(A) a container enclosing said reels, said container including:

(1) a top,

(2) a bottom,

(3) two converging flat side walls joined at an apex,

(4) an open portion at the divergent ends of said side walls opposite said apex,

(5) said bottom sloping downwardly from said apex to said open portion, and

(6) at least one movable closure member across said open portion sealably engaging the exterior of said container about said open portion,

(B) a lint collection chamber fastened to the top of said container, said chamber including:

(1) a top,

(2) a bottom,

(3) two converging flat side walls joined at an apex and being substantially parallel to the side walls of said container,

(4) an open portion at the divergent ends of said chamber side walls opposite said apex, and

(5) at least one movable closure member across the open portion of said chamber sealably engaging the exterior of said chamber about said open portion,

(C) a suction device fastened to a side wall of said chamber,

(D) a conduit having one end with access to the interior of said chamber and extending into said container adjacent said open portion from the top of said container to a position wherein the other end is adjacent the lowest portion of said bottom of said container,

(E) a pair of slidably removable spaced filter screens spaced from and substantially parallel to each side wall of said chamber,

(1) all of said screens being closer to the side walls than the said one end of the conduit,

(2) one screen of each pair being of a coarser mesh than the other screen,

(3) the coarser screens being placed in said chamber interiorly of the other screens,

(4) said coarser screens sealingly abutting each other at an apex substantially parallel to the apex of said chamber side wall apex, and

(5) said other screens sealingly abutting each other at an apex intermediate and substantially parallel to the apexes of said coarser screens and said chamber side walls,

(F) an elbow-shaped rotatable nozzle in each side wall directed into the interior of said container toward said open portion of said container and said conduit,

(1) said nozzles providing free passage of air from the exterior of said container to the interior in the form of directable streams in accordance with the demand requirements of said suction device;

whereby said streams may be directed along the bottom

of said container toward said conduit to give optimum cleaning in accordance with the type of yarn on said supply reels.

3. A lint collector for a loom having a plurality of supply reels comprising:

(A) a container adapted to enclose said reels having:

- (1) a top,
  - (2) a bottom,
  - (3) two converging flat side walls joined at an apex,
  - (4) an open portion at the divergent ends of said side walls opposite said apex,
  - (5) said bottom sloping downwardly from said apex to said open portion,
  - (6) at least one movable closure member across said open portion sealably closing said open portion,
- (B) a collection conduit having an intake opening within said container proximate the lowest portion of said bottom,
- (C) means including a suction source joined to said collection conduit for collecting lint carried by said conduit,

5

10

15

20

(D) at least one elbow-shaped rotatably adjustable nozzle in each side wall of said container directable toward said open portion of said container,

(1) said nozzles being adapted to supply air from the exterior of said container to the interior thereof in the form of directable streams in accordance with the demand requirements of said suction source whereby said streams may be directed along the bottom of said container to sweep any lint within said container toward said intake opening.
